CONSTANT LEVEL LUBRICATING DEVICE FOR BEARINGS

Original Filed Aug. 8, 1930

Inventor:
Frank E. Case,
by *Charles V. Tullar*
His Attorney.

UNITED STATES PATENT OFFICE

FRANK E. CASE, OF ERIE, PENNSYLVANIA, ASSIGNOR TO GENERAL ELECTRIC COMPANY, A CORPORATION OF NEW YORK

CONSTANT LEVEL LUBRICATING DEVICE FOR BEARINGS

Application filed August 8, 1930, Serial No. 473,934. Renewed June 18, 1932.

My invention relates to constant level lubricating devices for bearings, and particularly to devices of this type employing a storage reservoir in which lubricant is contained 5 below atmospheric pressure, above an outlet formed in the lower portion thereof, and from which the flow of oil is regulated by the admission of air to the upper portion of the reservoir.

10 In lubricating devices of the type with which my invention is concerned, the storage reservoir is filled by supplying oil thereto, usually under pressure, through a nozzle inserted in a filling passageway. After the reservoir is full the lubricant overflows therefrom, and heretofore to avoid flooding the bearing some means, such as a valve, has been used for preventing this overflow from entering the feeding chamber during filling of 15 the reservoir. This has the disadvantage that an attendant may forget to close it before filling or to open it after filling, either case giving very undesirable results, by respectively flooding the bearing or cutting off 20 the supply of oil when it is needed. To avoid this possibility of error a porous obstruction is sometimes used which normally feeds the oil to the bearing and serves to limit the flow of oil thereto, but if the oil level is appreciably 25 increased over the normal level, the rate of flow may be undesirably increased. It has become customary to provide some means for indicating when the reservoir is full but this indication is generally not in evidence until 30 the amount of oil has increased considerably over normal conditions in the chamber into which the oil has overflowed from the reservoir. The result is that when the filling operation is completed the oil level in the feeding 35 chamber has been raised appreciably and the rate of flow of lubricant from the feeding chamber to the bearing is undesirably increased.

It is an object of my invention to construct 40 a lubricating device of the character set forth in which there is no overflow chamber so that when the filling nozzle employed in filling the reservoir is removed, the level of lubricant from which oil is fed to the bearing remains substantially constant. I accomplish 45

this by constructing a constant level lubricating device comprising a storage reservoir adapted to contain lubricant below atmospheric pressure, and having an opening in the lower portion thereof. A feeding chamber 55 is provided communicating with the bearing and with the opening in the lower portion of the reservoir, and having a passageway thereinto formed and arranged with respect to the opening in the lower portion of the 60 reservoir so as to provide for introducing a filling nozzle therethrough to fill the reservoir and prevent the flow of lubricant into the feeding chamber during filling of the reservoir. A vent tube communicating directly 65 with the passageway and the upper portion of the reservoir is provided to regulate the lubricant flow from the reservoir to the feeding chamber and to maintain the oil level in the feeding chamber at a substantially con- 70 stant level.

My invention will be more fully set forth in the following description referring to the accompanying drawing and the features of novelty which characterize my invention 75 will be pointed out with particularity in the claims annexed to and forming a part of this specification.

In the drawing the single figure is a cross-sectional view of a bearing and lubricating 80 device embodying my invention.

Referring to the drawing, a shaft 1 is journaled in a bearing 2. A pocket 3 is formed at one side of the bearing 2 communicating therewith by a side opening 4, and opens at 85 the bottom into a feeding chamber 5 below the opening 4. Oil is fed to the bearing at a uniform rate from a substantially constant level in the feeding chamber by the capillary action of an absorbent material 6 contained in the pocket 3. In order to exclude dust and dirt from pocket 3 and afford access thereto, a cover 7 is provided having a vent opening therein so that the air pressure in the pocket 3 and chamber 5 will remain at 90 substantially atmospheric pressure, the air being admitted to the chamber 5 through the absorbent material 6 and an opening 9 at the upper portion of chamber 5 communicating with the pocket 3. The lubricant supply for 100

the feeding chamber 5 is obtained by means of an opening 10 which extends between the lower part of the feeding chamber and the lower part of a storage reservoir 11, which latter contains a supply of oil below atmospheric pressure for the chamber, the flow of lubricant therefrom being regulated by controlling the admission of air thereto.

In accordance with my invention the means 10 for supplying oil from the reservoir to the feeding chamber and maintaining it at substantially constant level is formed and arranged to provide for introducing a filling tube therethrough to direct oil into the reservoir without causing any change in the lubricant level in the feeding chamber, and without causing any appreciable change thereof after the reservoir is full and the filling tube is removed. This is obtained by forming the 15 opening 10 in the feeding chamber 5 as the lower end of a passageway 12 for introducing a filling nozzle 13, the passageway having a small recess or overflow receptacle 14 formed therein communicating with the lower end of 20 a vent tube 15 which opens at its upper end into the upper portion of the storage reservoir.

The upper part of the opening of the vent tube 15 into the recess 14 is formed at the desired height of the lubricant level in the feeding chamber 5, and the passageway 12 communicates with the feeding chamber between the recess and opening 10. The portion 16 of the passageway between the recess and the 30 opening 10 is restricted to fit the filling nozzle, so that when it is placed therein it prevents the flow of lubricant to the feeding chamber from the reservoir or passageway recess so that filling of the reservoir causes no 35 change in the lubricant level in the feeding chamber. A cover 17 is provided over the passageway 12 to exclude dust and dirt therefrom and has a vent opening formed therein so that the air pressure in the passageway 40 remains at substantially atmospheric pressure. Hence, the level of the lubricant in the recess is the same as the level in the feeding chamber, as they are both at substantially 45 atmospheric pressure and directly connected by the passageway 16.

When lubricant is fed to the bearing, the level in the feeding chamber and recess drops exposing the vent tube opening in the recess 55 14 and admitting air into the reservoir. This causes a flow of lubricant from the reservoir through opening 10 into the feeding chamber and recess and the consequent rise of lubricant therein until the opening of the vent 60 tube in the recess 14 is closed, thus preventing further admission of air into the reservoir, the flow of lubricant therefrom stopping when the pressure due to the air and lubricant in the reservoir equals atmospheric 65 pressure. In this way the oil level in the feed-

ing chamber is maintained at a substantially constant level at all times.

When it becomes necessary to fill the reservoir a filling nozzle 13 is introduced through the passageway 12 into the restricted portion 70 16 and the opening 10 directing the lubricant into the reservoir and preventing the flow of oil into the feeding chamber. When the reservoir is full, lubricant overflows through the vent tube into the recess and out between the walls of the passageway 12 and nozzle 13, or through a groove in the passageway or nozzle as may be desired. This gives the attendant an indication that the reservoir is 75 full. When the nozzle is removed the excess lubricant in the passageway above the recess flows to the feeding chamber but there is no appreciable change in the lubricant level in the feeding chamber as this amount is very 80 small compared to that of the feeding chamber. As no lubricant flows into the feeding chamber during filling and as the level of lubricant in the chamber remains substantially constant on the removal of the filling nozzle, there is no disturbance in the constant and uniform supply of lubricant to the 85 bearing.

I have illustrated my improved lubricating device in connection with a bearing and shaft, but it is apparent that it may be used in any other connection where a constant level lubricating device is desirable. Moreover, modifications of my invention, which I have illustrated and described, will occur to those skilled in the art. I desire it to be understood, therefore, that my invention is not to be limited to the particular arrangement disclosed, and I intend in the appended claims to cover all modifications which do not depart from the spirit and scope of my 90 invention.

What I claim as new and desire to secure by Letters Patent of the United States, is:

1. In combination with a bearing, a lubricating device comprising a storage reservoir adapted to contain lubricant below atmospheric pressure, said reservoir having an opening in the lower portion thereof, a feeding chamber communicating with said bearing and the opening in the lower portion of said reservoir, said feeding chamber having a passageway thereinto, a vent tube communicating with the upper portion of said reservoir and directly with said passageway, said passageway being formed below the opening of said vent tube into the same and arranged to provide for introducing a filling nozzle therethrough into the opening in the lower portion of the reservoir to direct lubricant into said reservoir and to prevent the flow of lubricant into said feeding chamber during filling of said reservoir.

2. In combination with a bearing, a lubricating device comprising a storage reservoir adapted to contain lubricant below at-

mospheric pressure, said reservoir having an opening in the lower portion thereof, a lubricant feeding chamber communicating with said bearing and the opening in said 5 reservoir, said feeding chamber having a passageway communicating therewith, a vent tube communicating with the upper portion of said reservoir and directly with the passageway in said feeding chamber at 10 substantially the desired level of oil in said feeding chamber, the diameter of the lower end of the passageway and the opening in said reservoir being made to fit a filling nozzle and aligned to provide for introducing 15 a filling nozzle therethrough to direct lubricant into said reservoir and to prevent the flow of lubricant into said feeding chamber during filling of said reservoir.

3. In combination with a bearing, a lubricating device comprising a storage reservoir adapted to contain lubricant below atmospheric pressure, said reservoir having an opening in the lower portion thereof, a feeding chamber communicating with the opening in said reservoir, a pocket opening to said bearing and communicating with said feeding chamber, absorbent material in said pocket for feeding lubricant therefrom to said bearing, said feeding chamber having a 25 passageway communicating therewith and formed with a recess therein, and means for providing communication between said recess and the upper portion of said reservoir, said passageway being formed and arranged 30 to provide for introducing a filling nozzle therethrough into the opening in the lower portion of the reservoir to direct lubricant into said reservoir and to prevent the flow of lubricant into said feeding chamber during filling of said reservoir.

4. In combination with a bearing, a lubricating device comprising a storage reservoir adapted to contain lubricant below atmospheric pressure, said reservoir having an outlet in the lower portion thereof, a feeding chamber communicating with said bearing and outlet, a vent tube opening into the upper portion of said reservoir and communicating with said feeding chamber, and means for 45 supplying lubricant to said storage reservoir through the outlet formed and arranged to provide for introducing a filling tube into the outlet to direct lubricant into said reservoir and to prevent the flow of lubricant into 50 said feeding chamber from said vent tube and said outlet during filling of said reservoir.

5. In combination with a bearing, a lubricating device comprising a storage reservoir 60 adapted to contain lubricant below atmospheric pressure, said reservoir having an outlet in the lower portion thereof, an overflow receptacle communicating with the upper portion of said reservoir, a feeding chamber 65 communicating with the outlet of said

storage reservoir and with said overflow receptacle, and means for supplying lubricant to said storage reservoir through the outlet formed and arranged to provide for introducing a filling tube into the outlet and overflow receptacle to direct lubricant into said reservoir and to prevent the flow of lubricant from said overflow receptacle and said outlet into said feeding chamber during filling of said reservoir.

6. In combination with a bearing, a lubricating device comprising a storage reservoir adapted to contain lubricant below atmospheric pressure, said reservoir having an outlet in the lower portion thereof, a feeding chamber communicating with the outlet in the lower portion of said reservoir, an overflow receptacle having a passage and an opening spaced apart in axial alignment with the outlet in the lower portion of said reservoir, a vent tube opening into the upper portion of said reservoir and at the normal oil level in said overflow receptacle, the passage and opening in said overflow receptacle and the outlet in said reservoir being formed to cooperate with a filling nozzle so as to prevent the flow of lubricant from said reservoir and said overflow receptacle to said feeding chamber when the filling nozzle is placed in the outlet in said reservoir for filling the same.

7. In combination with a bearing, a lubricating device comprising a storage reservoir adapted to contain lubricant below atmospheric pressure and having an outlet in the lower portion thereof, an overflow receptacle having an opening in the lower portion thereof, a vent tube opening into the upper portion of said reservoir and at the normal oil level in said overflow receptacle, a feeding chamber communicating with the outlet in the lower portion of said reservoir and with the opening in said overflow receptacle, said overflow receptacle also being provided with an extension having a passage in axial alignment with the outlet in the lower portion of the reservoir and the opening in the overflow receptacle, so as to provide for introducing a filling tube through said extension and opening into the outlet for directing lubricant into said reservoir and to prevent the flow of lubricant into said overflow receptacle and into said feeding chamber during filling of said reservoir and receptacle.

8. In combination with a bearing, a lubricating device comprising a storage reservoir adapted to contain lubricant below atmospheric pressure and having an outlet at the lower portion thereof, an overflow receptacle 125 communicating with the upper portion of said reservoir and having an opening in the lower portion thereof, a feeding chamber communicating with the outlet in the lower portion of said reservoir and with the open-

ing in said overflow receptacle, a pocket opening to said bearing and communicating with said feeding chamber, absorbent material in said pocket for feeding lubricant therefrom
5 to said bearing, a tubular extension of said overflow receptacle in axial alignment with the outlet in the lower portion of said reservoir and the opening in said overflow receptacle, the relation of said tubular extension
10 and the openings in the lower portions of said reservoir and overflow receptacle being such as to provide for introducing a filling nozzle into said outlet to direct lubricant into said reservoir and to prevent the flow of
15 lubricant into said feeding chamber during filling of said reservoir.

In witness whereof, I have hereto set my hand this 6th day of August, 1930.

FRANK E. CASE.
